CLAIM

The ornamental design for a wireless charger, as shown and described.

DESCRIPTION

FIG. 1 is a front, left, top perspective view of a wireless charger, showing my new design;

FIG. 2 is a rear, right, bottom perspective view thereof;

FIG. 3 is a front, right, top perspective view thereof;

FIG. 4 is a front elevational view thereof;

FIG. 5 is a rear elevational view thereof;

FIG. 6 is an enlarged, left side view of the wireless charger;

FIG. 7 is an enlarged, right side view thereof;

FIG. 8 is an enlarged, top plan view thereof;

FIG. 9 is an enlarged, bottom plan view thereof; and,

FIG. 10 is an enlarged front, left, top perspective view of the wireless charger shown in an alternate configuration.

The dashed broken lines in the figures are for the purposes of illustrating portions of the wireless charger and form no part of the claimed design.

The short-short-long dashed broken lines immediately adjacent to the claimed areas in the views represent the boundaries of the design and form no part of the claimed design.
